(57) **CLAIM**

The ornamental design for a beanie with an LED headlamp, as shown and described.

DESCRIPTION

FIG. 1 is a perspective view of a beanie with an LED headlamp, showing my new design in an environment of use in a first worn configuration;

FIG. 2 is a perspective view thereof, illustrated in an environment of use in an alternate worn configuration;

FIG. 3 is a perspective view thereof, illustrated in an environment of use in yet another alternate worn configuration;

FIG. 4 is a perspective view thereof, illustrated in an environment of use in yet another worn configuration;

FIG. 5 is a perspective view thereof, illustrated in yet another alternate configuration with the environment removed;

FIG. 6 is a perspective view thereof, illustrated in yet another alternate configuration with the environment removed;

FIG. 7 is a perspective view thereof, illustrated in yet another alternate configuration with the environment removed;

FIG. 8 is a perspective view thereof, illustrated in yet another alternate configuration with a cuff portion folded-down and the environment removed;

FIG. 9 is a front elevational view of FIG. 8;

FIG. 10 is a right-side elevational view of FIG. 8;

FIG. 11 is a perspective view thereof, illustrated in another configuration with the cuff folded-up and the environment removed;

FIG. 12 is a front elevational view of FIG. 11;

FIG. 13 is a rear elevational view of FIG. 11;

FIG. 14 is a right-side elevational view of FIG. 11, the left-side elevational view being a mirror image thereof and therefore not shown;

FIG. 15 is a top plan view of FIG. 11; and,

FIG. 16 is a bottom plan view of FIG. 11.

The broken lines in FIGS. 1-4 illustrating people wearing the beanie with an LED headlamp are for the purpose of showing environmental subject matter only and form no part of the claimed design. The remaining broken lines depict stitching, and do form part of the claimed design.
